CIRCULATORY LOOP

Edmund E. Allyne, Cleveland, Ohio, assignor to
 Allyne Laboratories, Inc., Cleveland, Ohio, a
 corporation of Ohio

Application July 24, 1933, Serial No. 681,994

2 Claims. (Cl. 62—118)

This invention relates to absorption type refrigeration apparatus and more particularly to an air cooled heat exchange device for efficiently cooling the boiler liquor in the still of an absorption refrigerating apparatus during the cooling period of the refrigerating cycle.

This invention is applicable to all absorption cycle refrigerating apparatuses, although it is of particular value in connection with the absorption cycle refrigerating systems disclosed in my copending applications, Serial Nos. 338,174, filed February 7, 1929, and 665,029, filed April 7, 1933.

As is well known by those skilled in the art, it is highly desirable to quickly cool the hot boiler liquor in the still-absorber during the cooling or off-heat period of the refrigerating cycle to ensure efficient absorption of the refrigerating agent in the boiler liquor.

Heretofore it has been proposed to use impounded or running water for this cooling but extended experiments have shown that this is not only impractical but inefficient.

Referring to the drawing, it will be seen that Fig. 1 is a diagrammatic layout of an absorption type refrigerating apparatus including the subject matter of the present invention.

Fig. 2 is a vertical section of the still-absorber taken on line 2—2 of Fig. 1.

Specifically referring to the drawing, 1 denotes a cylindrical or other shaped still-absorber or boiler which is heated by a gas burner 2. It will be understood that the still-absorber or boiler may be heated by any suitable means, such as an oil burner or electrical resistance coil, as this forms no part of the present invention.

An outlet pipe 3 extends from the upper part of the still-absorber 1 and is preferably in the form of an attenuated vertical conduit which may act as a rectifier. The pipe 3 is U-shaped and discharges adjacent the bottom of a liquid seal or trap 4. Extending upwardly about half way within the liquid trap is an overflow return pipe 5, and the trap is filled with a suitable liquid, such as water or mercury, up to the level of this pipe 5.

Also extending upwardly through the bottom of the trap 4 is the U-shaped gas conduit 7 leading to a condenser, evaporator or other portion of the refrigerating apparatus designated by the numeral 8. It will be seen from the drawing that the lower end of the pipe 7 terminates slightly above the height of the pipe 5 and the level of the liquid in the trap 4.

In closed communication with the still-absorber 1 is a heat exchange device consisting of a down

leg 10 and an up leg 11 with the portion of the heat exchanger between the leg sections 10 and 11 in the form of a U-shaped horizontal loop 9. The parallel sections of the U-shaped loop or pipe 9 lie in a horizontal plane and are provided with air cooled heat radiating fins 12 in contact therewith. The lower end of gas return pipe 5 leading from the trap 4 communicates with the heat exchanger at a point in the down leg 10 just beyond the bent section 13 at the lower end of 10 the vertical portion of the down leg. This bent section 13 acts as a liquid trap and ensures that gas passing through pipe 5 will circulate in the direction of the arrows.

The down leg 10 extends from a low level in the 15 still-absorber, while the terminus of the up leg 11 is just below the level of the liquid 14 in the still at the end of the heating cycle. It is preferable to continue the pipe 11 upwardly at an oblique angle after it enters the still and to offset it so that it lies in approximately the center of the still as shown in Fig. 2.

In operation, heat is applied to the still 1 to drive off or boil the ammonia absorbed in the liquid 14. The gas evolved passes from the still 25 1 through rectifier pipe 3 and bubbles upwardly through the liquid 6 in the trap 4, thence passing out of the trap through pipe 7 to the condenser or evaporator 8. Any entrained water is removed from the gas in passing through the 30 liquid of the trap and the surplus gravitates downwardly through pipe 5 into the heat exchanger or circulator coil 9.

Upon completion of the heating period, the 35 heat is cut off and the liquefied ammonia collected in the evaporator volatilizes and absorbs heat units from the refrigerator or other space in which the evaporator is confined, whereupon being transformed into a gas, the reverse action 40 from the heating period ensues. Thus the gas during the cooling cycle returns through gas pipe 7 and back through pipe 5 into the horizontal section of the loop 9 just beyond the trap 13, creating a circulation or surging of the still liquid 14 therethrough as indicated by the arrows. 45 No gas can bubble upwardly through leg 10 on account of the weight of liquid in trap 13. In following this circuitous path, the liquid in the still is rapidly circulated and its heat efficiently dissipated by means of the air cooled fins 12 attached to the horizontal portions of the heat exchanger loop 9. As disclosed in my copending applications, Serial Nos. 338,174 and 665,029, I 50 may place the circulatory heat exchanger in a flue to increase the circulation of air passing the 55

fins to dissipate the heat. The latent heat of the still liquor is therefore readily removed and permits the complete absorption of the ammonia gas in the liquid 14 of the still. After the absorption is complete, the burner 2 is again turned on to drive off the absorbed ammonia for further condensation and refrigeration.

This arrangement of the heat exchanger 9 with its down leg 10 circulating liquor from adjacent the bottom of the still-absorber and discharging cooled fluid adjacent the central portion of the still-absorber, accomplishes the dual function of circulating the hottest liquor to the heat exchanger first, as well as permitting cooled liquid 15 and gas to escape into the still near the surface of the boiler liquor supply. The elongated oblique section of the up leg 11 also allows the entrained gas bubbles to break up with little noise and with a minimum of foaming of the liquor.

20 What I claim is:

1. In an absorption cycle refrigerating system, a still-absorber, a heating burner therefor, an

outlet conduit leading from said still-absorber to an elevated liquid trap, a closed circulating loop provided with a series of spaced vertical heat conducting fins arranged thereon depending from said still-absorber, the major portion of the said loop lying in both the horizontal and parallel planes thereto, a gas return conduit leading from the said liquid trap to the said circulating loop and communicating therewith at a point slightly below the major horizontal portion thereof. 5

2. In an absorption cycle refrigerating system, a still-absorber, a heating burner therefor, a gas outlet conduit leading from the top of said still, an air-cooled closed circulatory loop comprising up and down legs and a major horizontal U- 15 shaped section depending from said still-absorber, a gas trap in the lowermost portion of the said down leg and a gas inlet conduit connected between the said gas trap and the said horizontal U-shaped section of the loop. 10
